UNITED STATES PATENT OFFICE.

ISIDOR GREENSAFT, OF NEW YORK, N. Y.

MOUNT FOR MANIPULATABLE FANS AND PERSONAL UTILITIES EQUIPMENT.

Application filed January 24, 1921. Serial No. 439,502.

To all whom it may concern:

Be it known that I, ISIDOR GREENSAFT, a citizen of the United States, and a resident of the borough of Manhattan, city, county, 5 and State of New York, have invented certain new and useful Improvements in Mounts for Manipulatable Fans and Personal Utilities Equipment, of which the following is a specification.

10 The object of my invention is the production, as an article of manufacture, of a rotatable hand fan and mount, designed more particularly for feminine use, the handle, and the casing of the operative parts, being 15 also adapted to containing and supporting, in convenient position for access and use, other adjunctive devices and objects of personal equipment; as hereinafter more fully set forth,—the invention consisting in the 20 specific construction, combination and arrangement of devices and parts described and claimed whereby the various functions are attained in a compact unitary contrivance.

25 In the accompanying drawings,

Fig. 1, is a front elevation, full size, of my personal utilities equipment mount, one of the vanes of the fan being broken away in part;

30 Fig. 2, is a central longitudinal sectional elevation taken upon plane of line 2—2, Fig. 1;

Fig. 3, is a sectional detail of the vane clamp on a larger scale showing spring tension as applied thereto;

35 Fig. 4, is a perspective view of the handle and cap removed therefrom;

Fig. 5, is an elevation of the rear side of my device, broken away in part the better 40 to show details of construction;

Fig. 6, is a section taken upon plane of line 6—6, Fig. 2;

Fig. 7, is an elevation of the inner side of the rear compartment closure, showing 45 the mirror;

Fig. 8, is an enlarged sectional elevation, taken upon plane of line 8—8, Fig. 5;

Fig. 9, is a like view taken at right angles to Fig. 8;

50 Fig. 10, is a diagrammatic view showing the inner or hub ends of the fan vanes detached and separated, but as correlated to each other;

Fig. 11, is a sectional detail taken upon 55 plane of line 11—11, Fig. 10;

Fig. 12, is an elevation, on a reduced scale,

of the device as folded into compact form for convenience in packing or carrying.

F, F, are the fan vanes, any desired plural number of which may be employed, three 60

by preference, as shown in the drawings. The inner or hub ends of these fan vanes F, F, are formed with arbor bearing holes f, f, for the rotatable arbor a; and also each with a protuberance f', and a recess f'',—the 65

protuberance f', on one vane fitting into the recess f'', of the adjacent vane when the vanes F, F, are radially positioned in equidistant 70

relation to each other as in Figs. 1, 5 and 6,—the interlocking being shown particularly in detail in Fig. 3. Figs. 10 and 11, 75

also show the protuberances f', and the recesses f'', as positioned and correlated to each other. This interlocking of the hub ends of 80

the fan vanes insures the proper spacing apart of the latter when arranged for use, 85

in which case the said hub ends of the vanes F, are held in such engagement and against an annular shoulder a', on the arbor a, by means of a thumb nut N, engaging with the 90

screw threaded outer extremity of said arbor a. A spring n, preferably countersunk in the nut N, may be interposed between the latter and the hub ends of the vanes F, F, as shown in Fig. 3, when elastic 95

resilient tensional pressure is desired to be exerted against said vanes, or the thumb nut may bear directly thereon as shown in Fig. 2. In either case, the nut N, affords 100

means whereby the vanes may be, mounted and held upon the arbor a, in such manner as to be rotatable therewith. When not desired for use, the vanes F, by simply reversing the nut N, may be loosened up and turned and folded into alignment with each 105

other and with the casing, so as not to protrude beyond each other or the casing,—thus adapting the device in this respect for convenient and compact packing, storage or transportation, as shown in Fig. 12.

110 The arbor a, is mounted on the front and rear walls of the works casing W, as shown in Fig. 2, and has rigidly attached to it within the said casing W, a pinion a'. This pinion meshes with a relatively large driving gear d, mounted loosely on the rotatable shaft e, which is supported also on and between the front and rear walls of the work casing W. The drive gear d, carries a spring pawl d', which engages peripherally with a 115

ratchet wheel e', rigid on the drive shaft e, to which latter is also rigidly attached a

pinion e^2 , which meshes with a segmental rack R, rockable on a fulcrum w, (Fig. 6) in the works casing W. A spring r, tends constantly to maintain said rockable segmental rack R, in retracted position, which is that shown in said Fig. 6, which is the normal position when the fan is not in use. The segmental rack R, is formed with a curved lever arm r', the free end of which 10 rests against the inner end of a push rod p, by means of which the segmental rack R, may be rocked against the resistance of the retractile spring r. The inner end of the push rod p, is provided with a cross pin 15 p', (Fig. 6) the ends of which project into slots w', w', in guide members w², w², rigid upon the inner side of the casing W, through which latter the outer portion of the push rod protrudes, and is formed at its outer extremity with a push button or equivalent 20 thumb contact piece p²,—a retractile spring p³, being interposed between the casing W, and said contact button p², which spring tends constantly to thrust the push rod p, 25 outward into the position shown in Figs 1, 5 and 6.

In operation, when the actuating rod p, is pushed inward against the resistance of its spring p³, (and also against the resistance of its retractile spring r, connected with the segmental rack R, as before stated) it 30 rocks the segmental rack R, on its fulcrum w, through the medium of the lever arm r', thereof, thereby causing the rack teeth to 35 rotate the pinion e², and ratchet wheel e', the latter acting through the spring pawl d', to rotate the drive wheel d, which in turn rotates the pinion a², and the arbor a, and hence effects the rotation of the fan vanes 40 F, F, mounted thereon as hereinbefore set forth,—the momentum thus imparted to the said fan vanes F, F, being sufficient to cause them to continue rotation during the retractile movement of the segmental rack R, 45 and push rod p, as effected by the springs p³, and r, when pressure on the push button p², is sufficiently relaxed,—the spring pawl d', by slipping over the teeth of the ratchet wheel e', admitting of this automatic restoration 50 of the operative parts to normal position without materially retarding the continued rotation of the fan vanes under the impetus imparted thereto by the inward thrust of the push rod p, as before stated. 55 Hence the intermittent reciprocation of the push or actuating rod p, will result in a corresponding but continuous rotation of the fan as long as the rod p, is thus manipulated.

60 The rear part of the works casing W, beyond the medial division wall w^x, is formed to accommodate a receptacle V, for a powder puff v', to the back of the hinged closure v², of which is secured a mirror v³. 65 The back or bottom v^x, (Fig. 2) of the puff

holder V, may have imposed thereon compact face powder or rouge. Thus the essentials of a "vanity" outfit are provided and incorporated with the works casing in conveniently accessible position for use when 70 required.

The outer face of the lid or closure v², of this "vanity" compartment is formed with an open face pocket v²², for a small open face watch or time piece t, which may be 75 inserted in the pocket v²², from the rear of the closure v², before the attachment of the mirror v³, thereto. Thus a glance at the "back" of the fan will always disclose the time.

The back part of the casing W, below the vanity outfit above described, is utilized as a container X, (Fig. 2.) for "make up" cosmetics etc.,—it being provided with hinged closure x'.

The bottom of the works casing W, is formed with a hollow shank S, which I utilize as a coin holder, the same being provided with a spring s', and follower or bearing plate s², and provision being made for 90 the introduction of coins thereunder through a slot s³, in one side of the coin holder S. The bottom of the coin holder s, is formed with a suitable finger opening s^x, to facilitate the insertion and removal of coins. 95 This device is shown upon an enlarged scale in Figs 8 and 9, which also illustrate more clearly the construction and arrangement of adjacent parts.

The metallic ferrule h, of the handle H, 100 is hinged at h', to the coin holder S, and may be held in closed relation thereto by snap lugs h². The handle H, preferably made of non-metallic material, is hollow, being formed with a vial compartment h³, and also with a compartment h⁴, for pins, etc., the two compartments h³, h⁴, being separated by a partition h⁵. The lower or end compartment h⁴, is closed by means of a screw cap h⁶, containing a cushion h⁷, for pins, needles, etc. The cushion h⁷, is also formed with a socket h⁸, for the insertion of the end of a pencil h, or equivalent marking device, 110 for use in conjunction with the memorandum tablet hereinafter mentioned.

The upper or ferrule end compartment h³, of the handle H, is adapted for use as a container for a vial i, for holding a liquid perfume for instance, or smelling salts, or in fact any substance desired for the comfort 120 or convenience of the user. To this end the neck of the vial i, is screw threaded externally, and provided with a screw cap i', which is also screw threaded externally for engagement with an internal screw thread 125 h⁹, formed for the purpose in the inner or ferrule end of the handle H, as shown in Figs. 2, 8 and 9.

The front side of the works casing W, is formed with a holder Q, for a memorandum 130

tablet *q*, which may be frictionally or otherwise detachably retained in position.

It will be seen that by my construction and arrangement of parts I attain a unitary contrivance embodying several functions all appertaining to the personal comfort and convenience of the user, and so completely arranged as to be conveniently manipulatable and portable.

10 By folding the fan vanes upon each other, and positioning them within the area of the works casing and by folding the handle thereover also, as exemplified in Fig. 12, the device may be carried in a ladies' hand or 15 opera bag or the like, or packed economically for storage or transportation.

What I claim as my invention and desire to secure by Letters Patent is,

1. A manipulatable hand mount of the character designated, comprising a rotatable fan and driving parts, the latter encased and consisting of a fan arbor, a pinion thereon, a loosely mounted driving gear meshing therewith and carrying a spring 25 pawl, a ratchet wheel rigidly mounted on a main shaft and engaging with said spring pawl, a pinion rigidly mounted on said main

shaft, a rockable segmental gear meshing therewith, a push rod for actuating said segmental gear formed with a cross pin 30 fitting in slotted stationary guide members, said guide members, and retractile springs tending constantly to hold the push rod and segmental gear in normal positions, for the purpose described.

2. In combination with a manipulatable hand mount of the character designated, and driving parts suitably encased, a rotatable fan consisting of a plurality of fan vanes hub perforated for attachment to a rotatable 40 arbor and also formed with interlocking parts, said rotatable arbor formed with a bearing shoulder and with a screw threaded outer extremity, and a nut engaging said threaded end of the arbor and adapted to 45 hold the vanes rigidly against said shoulder thereon, said nut being countersunk on its inner face and containing a bearing spring, for the purpose described.

ISIDOR GREENSAFT.
